UNITED STATES PATENT OFFICE.

GEORGE ABBOTT, JR., OF MOORESTOWN, NEW JERSEY.

MILK-CAN TOP.

SPECIFICATION forming part of Letters Patent No. 288,391, dated November 13, 1883.

Application filed August 27, 1883. (No model.)

To all whom it may concern:

Be it known that I, GEORGE ABBOTT, Jr., a citizen of the United States, and a resident of Moorestown, Burlington county, New Jersey, have invented certain Improvements in 5 Milk-Can Tops, of which the following is a specification.

My invention relates to improvements in that class of milk-cans which are provided 10 with inner and outer covers; and the main object of my invention is to so combine a milk-can top with an inner cover and a hinged outer cover, and with appliances explained hereinafter, that the covers may be fastened 15 simultaneously and unfastened simultaneously.

Other objects of my invention and devices 20 for carrying them into effect are too fully explained hereinafter to need preliminary description.

Further objects of my invention are to afford opportunities for locking the covers, and for sealing the outer cover.

In the accompanying drawings, Figure 1, 25 Sheet 1, is a vertical section of my milk-can top; Fig. 2, a plan view; Fig. 3, a view showing the character of the opening in the outer cover; Fig. 4, Sheet 2, a sectional view of the milk-can top as it appears when the covers 30 have been opened and turned back; and Fig. 5, a sectional plan on the line 1 2, Fig. 1.

A casing, A, preferably of cast-iron, has at 35 its lower edge an annular flange, a, which is secured to the sheet-metal body of a milk-can, the said body being similar to those of cans in common use for the transportation of milk.

The casing A has an internal annular flange, b, having a trued upper surface, forming a bearing for the trued under surface of the inner cover, D, the latter having on its upper 40 surface, near the outer edge, three, or any other appropriate number of inclined planes, x, (shown in Fig. 5,) which, by turning the cover, can be brought beneath lugs or ribs d on the interior of the casing, thereby locking 45 the said inner cover to the internal rib, b, and forming therewith a tight joint. This inner cover has at its edge as many notches d' as there are lugs d, so that when the former covers 50 coincide with the latter the cover may be lowered onto or raised from the flange b'.

A central stem, E, extends upward from the inner cover, D, through an outer cover, F, which is hinged at y to the casing A, the stem E being provided above this cover with a 55 knob or enlargement, f, by turning which the inner cover may be locked to its bearing or released therefrom, and when thus released the said inner cover D may be raised until it is in contact with the outer cover, and both 60 covers may then be turned back to the position shown in Fig. 4.

The stem E has a flange or collar, v, which prevents the cover F from being raised until the inner cover is in a given position—that is, 65 when it is unlocked from the lugs d in the casing—and when the notches in the edge of the inner cover coincide with the said lugs then the inner cover can be elevated, for a rib, e, on the stem E can pass through and slide in a 70 notch, i, in the opening h, Fig. 3, of the outer cover; but when the covers are depressed the outer cover is clear of the upper end of the rib e, and the stem E and inner cover can be turned and locked, the outer cover being at 75 the same time locked, owing to the flange v of the stem.

The object of the rib e is to facilitate the adjustment of the inner cover to its place in lowering it and preparatory to locking. The outer 80 cover cannot be raised until the upper end of the said rib e coincides with the notch i in the edge of the opening of the outer cover, F, and as long as the inner cover is elevated it is prevented by the rib from turning, and in lowering 85 the inner cover it is so guided by the rib that the notches in the edge of the cover will coincide with lugs d in the interior of the casing A. As soon as the cover reaches its seat on the flange b, however, the upper end of the 90 rib e will be clear of the outer cover, and hence will present no obstacle to the turning and locking of the inner cover.

The pilfering of milk from cans during transportation is a common occurrence; hence I 95 secure the covers in such a manner that milk cannot be abstracted from the can without detection. I pivot to the upper end of the stem E an arm, G, and when this arm occupies a position between the two projections m m on 100 the outer cover, F, it is an indication that the covers are in a condition to be raised and

turned back; but in preparing a filled can for transportation I turn the stem E of the inner cover until the latter is tight to its bearings, and the can thereby sealed, when the arm G 5 will be near but not generally in contact with a projection, p' , on the said outer cover, and the arm can then be bound to this projection by passing a wire or cord through holes in both and properly fastening the same, so that 10 there can be no dislodgement of the inner cover from its seat until the removal of the fastening. A proper seal may be attached to the cord or wire, so as to indicate any attempt to unfasten it; but there are occasions when 15 the can should be closed without being sealed, so as to be promptly opened, as, for instance, when the can is at its destination; hence the intermediate projection, p , on the cover. When a portion of the contents of the can has 20 been removed, and it is desirable to properly close the same, the stem is turned until the intermediate projection, p , which, when the arm is released, will retain the cover in a substantially closed condition without said cover 25 being tightly bound to its seat.

I claim as my invention—

1. A milk-can top in which the following elements are combined, namely: first, the casing A, its internal flange, b , and internal projections, d ; second, the outer cover, F, hinged to the casing; third, the inner cover, D, constructed to be confined to the flange b by the said projections d , and to be released therefrom, and having a stem, E, arranged to slide in the said cover F, and constructed to secure 30 35

the same simultaneously with the locking of the inner cover, all substantially as set forth.

2. The combination of the casing A, its flange b and projections d , and the outer cover, F, hinged to the said casing, with the inner cover, D, notched at the edge, and having a stem, E, passing through the outer cover, and provided with a rib, e , adapted to a notch in the said cover, and with a flange or collar, 40 45 v , by and between which and the upper end of the rib the said cover may be confined, substantially as described.

3. The combination of the casing A, the outer cover, F, hinged thereto, and having projections $m m$, the inner cover, D, constructed to be locked to and released from a bearing in the casing, and having a stem, E, passing through and constructed to lock and release the outer cover, and having a pivoted arm, 50 55 G, adapted to fit between the said projections, substantially as set forth.

4. The combination of the casing A, having a flange, b , and projection d , and the outer cover, F, hinged to the said casing, and having projections $p p'$, with the notched inner cover having inclined planes x , and a stem, 60 65 E, passing through the outer cover, with the arm G, pivoted to the stem, all substantially as specified.

In testimony whereof I have signed my name to this specification in the presence of two subscribing witnesses.

GEO. ABBOTT, JR.
